UNITED STATES PATENT OFFICE

GEORGE J. BRETT, OF LANCASTER, PENNSYLVANIA

ANÆSTHETIZER

Application filed September 29, 1928. Serial No. 309,345.

The principal object of the present invention is to provide means for anæsthetizing or administering anæsthetics which will hereinafter be referred to descriptively, and not by way of limitation, as oxygen and nitrous oxide according to the symptoms displayed by the patient.

Another object of the invention is to provide for controlling the volume of mixture of regulated gases, by number of gallons per minute, administered to the patient, without shock to the patient and according to the stage of anæsthesia of the patient.

To these and other ends hereinafter set forth or appearing the invention may be said to comprise the improvements hereinafter described, and also an anæsthetizer having two sets of valves arranged in series and of which one is to be set to fix the percentage 20 of nitrous oxide and of oxygen in the mixture, and of which the other is adapted to control the quantity per unit of time of the mixture administered gradually and according to the symptoms of the patient and in 25 order to avoid subjecting the patient to what might be called sudden shocks.

In the following description reference will be made to the accompanying drawings forming part hereof and in which

30 Figure 1 is a plan view of an anæsthetizer embodying features of the invention and showing the same mounted upon a pedestal or stand.

Fig. 2 is a side view partly in section of 35 the top portion of the same.

Fig. 3 is a front view of the panel or table drawn to an enlarged scale.

Fig. 4 is a sectional view taken generally on the line 4-4 of Fig. 3.

40 Fig. 5 is an edge view of the table looking from right to left in Fig. 3, and

Fig. 6 is a rear view of the table shown in Fig. 3.

1 is a stand having vertically adjustable 45 arms 2 to which the table, generally indicated at 3, is pivoted. The stand accommodates the tank 4 for oxygen and the tank 5 for nitrous oxide. Referring more particularly to Fig. 6, 6 is a nitrous oxide gas inlet connection, and 7 is an oxygen gas inlet connec-

tion. There is an outlet connection 8 including a connection 9 for the bag 10. The outlet connection is provided with a valve 11 and is shown as fitted with means 12 for administering gas to the patient. 13 is a mixer and it includes a valve operated by the lever 14, and this lever operated valve controls the volume of regulated gas by number of gallons flow per unit of time to the respiratory reservoir 15, which is provided with a heater 60 to keep the temperature of the gas constant, and with a gauge 16 which serves to show the pressure in the reservoir and to indicate the pressure in the bag 10. The oxygen connection includes a pipe 17 having a normally closed valve 18 therein and leading direct to the outlet 8. The oxygen connection also includes a branch pipe 19 leading to the mixer 13 and including a pressure regulator 20 having a gauge and also screw means 21 70 which operate the oxygen valve provided by the regulator.

The nitrous oxide connection includes a pipe 22 leading direct to the reservoir 15 and including a normally closed valve 23. The nitrous oxide connection also includes the branch pipe 24 leading to the mixer 13 and including a pressure regulator 25 having a gauge 26. The valves 20 and 25 control the individual percentage of gases in the mixture.

It may be remarked that valves 20 and 25 are intended to be set to fix the percentage of gases in the mixture administered to the patient, and that there is another valve 13 operated by the lever 14 for controlling the volume of the mixture administered to the patient.

The use of the apparatus for anæsthetizing a patient may be described as follows:

The pressure regulators 25 and 20 may be set to deliver a mixture of oxygen and nitrous oxide in appropriate proportions, which may be indicated as 7 parts oxygen to 93 parts nitrous oxide by volume. The physician carefully notes the symptoms of the patient and has recourse to the chart or dial A, and having regard to the symptoms, the physician manipulates the handle 14 controlling the volume of the mixture as the

95

100

symptoms require, and the control may be made gradual in order to avoid shocks to the patient. The valves 18 and 23 may be regarded as emergency valves and used in case of necessity for administering additional volumes of nitrous oxide or oxygen.

From the foregoing description it is evident that the described anæsthetizer in its use depends principally upon the symptoms exhibited by the patient and that the latter is not subjected to sudden shocks but is gradually and properly anæsthetized.

It will be obvious to those skilled in the art to which the invention relates that modifications may be made in details of construction and arrangement and matters of mere form without departing from the spirit of the invention which is not limited to such matters or otherwise than the prior art and 20 the appended claim may require.

I claim:

An anæsthetizer including in combination a mixer, valve means for supplying oxygen and nitrous oxide respectively in regulated proportions to the mixer, a respirator reservoir in communication with the mixer, an outlet including a bag, both bag and outlet being in communication with the respirator reservoir, a valve for regulating the quantity per unit of time of mixture delivered from the mixer to the respirator reservoir, a pressure gauge on the respirator reservoir, a by-pass nitrous oxide connection to the respirator reservoir for diluting the mixture 35 therein, and a by-pass oxygen connection to the outlet.
